DESIGN FOR A COMBINATION BAG AND GARMENT

Diana Morgan Jackson, New York, N. Y.

Application September 4, 1941, Serial No. 103,154

Term of patent 14 years

To all whom it may concern:

Be it known that I, Diana Morgan Jackson, a citizen of the United States, residing at 231 East 76th Street, city of New York, in the county of New York and State of New York, have invented a new, original, and ornamental Design for a Combination Bag and Garment, of which the following is a specification, reference being had to the accompanying drawings, forming part thereof, wherein:

Fig. 1 is a view of the combination bag and garment of my design illustrated in carrying position, the robe being completely folded into the bag piece;

Fig. 2 is a view of the combination bag and garment shown in Fig. 1 with the robe partially unfolded from the bag;

Fig. 3 is a rear view of the combination bag and garment shown in Fig. 1 with the back or bag piece raised, and the robe completely unfolded;

Fig. 4 is a front view of the combination bag and garment shown in Fig. 1, in wearing position; and

Fig. 5 is a rear view of the combination bag and garment shown in Fig. 1, in wearing position.

The piece on the back of the robe as shown in Fig. 5 comprises the bag into which the garment is folded for carrying.

I claim:

The ornamental design for a combination bag and garment substantially as shown and described.

DIANA MORGAN JACKSON.
